UNITED STATES PATENT OFFICE.

WILLIAM R. NOE, JR., OF EAST ORANGE, NEW JERSEY, ASSIGNOR TO WILLIAM R. NOE, OF EAST ORANGE, NEW JERSEY.

CANDLE-SHADE SUPPORT.

No. 902,597.

Specification of Letters Patent.

Patented Nov. 3, 1908.

Application filed October 10, 1907. Serial No. 396,716.

To all whom it may concern:

Be it known that I, WILLIAM R. NOE, Jr., a citizen of the United States, residing in East Orange, in the county of Essex and State of New Jersey, have invented a certain new and useful Improvement in Candle-Shade Supports, of which the following is a specification.

The invention relates to candles used for table decoration and lighting and more particularly to means for supporting the ornamental shades for such candles.

The object of the invention is to provide a support which shall protect the candle flame and lessen the danger of igniting the shade, and also permit light to radiate in all directions without shadows.

The invention consists in certain novel features and details of construction by which the above objects are attained, to be hereinafter described and pointed out in the claims.

The accompanying drawings form a part of this specification and show an approved form of the invention.

Figure 1 is a side elevation of a candle-holder equipped with the invention and carrying a decorative paper shade. Fig. 2 is a corresponding vertical section, partly in elevation. Fig. 3 is a plan or top view with the shade removed.

Similar letters of reference indicate the same parts in all the figures.

A is a tube of metal preferably enameled or otherwise coated in imitation of a candle, having a contracted upper end A¹ and adapted to receive a candle B within it forced upwardly to the contracted end by a follower C and helical spring C¹. The lower end A² of the tube is arranged to be received in a candlestick or other suitable socket. All these parts may be understood to be of the usual or any approved construction.

D is an openwork annular gallery attached to the tube A near the upper end, comprising a circular flange carrying an ornamental vertical flange or rail, the whole forming an annular socket in which is received a removable shade-holder of glass having a cylindrical

body F surrounding the flame of the candle, and a neck F¹ at the lower end held within the gallery D. The upper end of the body is contracted to form a shoulder F² on which is supported the shade M, shown as an ornamental paper shade in imitation of flowers but which may be of any suitable material and form adapted to be supported upon the shoulder F².

Contact of the candle-flame with the inflammable material of the shade is prevented and the flames protected from air currents, while the transparent character of the support avoids shadows. The support may be tinted or otherwise ornamented and thus add to the decorative effect.

I claim:

1. An improved article of manufacture comprising a tubular holder in the form of a candle and having a contracted upper end with its lower end adapted to be received in a candlestick, a gallery supported upon said holder below said contracted end, a transparent shade holder removably supported on said gallery and having its upper end contracted to form a shoulder, and an ornamental shade removably supported upon said shoulder.

2. The combination with a tubular holder the lower end of which is adapted for removable engagement with a socket and the upper end contracted, of a spring actuated follower in said holder, a candle supported on said follower and projected through said contracted end, a gallery on said holder, a support of glass mounted in said gallery and surrounding said candle, and having a contracted upper end forming a shoulder, and an ornamental tapered shade removably held on said shoulder.

In testimony that I claim the invention above set forth I affix my signature, in presence of two witnesses.

WM. R. NOE, JR.
